CLAIM

The ornamental design for a display screen or portion thereof with a graphical user interface, as shown and described.

DESCRIPTION

A portion of the disclosure of this patent document contains material which is subject to copyright protection. The copyright owner has no objection to the facsimile reproduction by anyone of the patent document or the patent disclosure, as it appears in the Patent and Trademark Office patent file or records, but otherwise reserves all copyright rights whatsoever.

The FIGURE is a front view of a display screen or portion thereof with a graphical user interface.

The outermost dot-dashed broken line rectangle depicts the display screen or portions thereof. The other dot-dashed broken lines depict boundaries of the claimed graphical user interface. All other broken lines depict portions of the graphical user interface. The broken lines form no part of the claimed design.
